UNITED STATES PATENT OFFICE.

HARRY F. WITTIG, OF BALTIMORE, MARYLAND, ASSIGNOR OF ONE-HALF TO A. O. BRUNMEL, OF BALTIMORE, MARYLAND.

ILLUMINATED LICENSE-TAG HOLDER.

Application filed December 16, 1921. Serial No. 522,810.

To all whom it may concern:

Be it known that I, HARRY F. WITTIG, a citizen of the United States, residing at Baltimore, in the State of Maryland, have invented certain new and useful Improvements in Illuminated License-Tag Holders, of which the following is a specification.

This invention relates to illuminated license tag holders and has for its objects

10 the following:—

To provide a holder which is equipped with an illuminating compartment, the latter having a license tag arranged therebelow and set at an angle to directly receive 15 the light rays on its face; to provide an inexpensively constructed holder which can be readily attached to any type of automobile; to provide a holder which may be formed to 20 carry one or more tags of conventional design, the tags being slidably engaged with and disengaged from the holder in a facile manner; and to provide a tag holder which is attachable directly to the bolts now employed for supporting the license tag per se, 25 thereby not only supporting the holder but also securing the tag therein.

Other objects of the invention will be more readily understood from the following description of the present preferred embodiment 30 of the invention taken in connection with the accompanying drawings, wherein:

Fig. 1 is a front elevational view of a tag holder constructed in accordance with this 35 invention showing a license tag arranged therein;

Fig. 2 is an end elevational view of the same;

Fig. 3 is a sectional view taken on the line 40 3—3 of Fig. 1;

Fig. 4 is a detail fragmentary sectional view showing to advantage the manner in which the license tag holder is mounted upon a vehicle;

Fig. 5 is a detail enlarged fragmentary and elevational view of the holder showing the license tag removed therefrom; and

Fig. 6 is a similar view of a modified form of holder.

50 The device of this invention consists of a holder or casing 7 preferably made of sheet metal having the lower margin thereof bent at right angles, as indicated at 8 with a lip 9 turned up in the front of the holder. The upper end of the body of the casing is bent

at right angles to provide a flange 10 to which is secured an illuminating compartment generally designated 11. This compartment is preferably of a semi-elliptical shape the front of which is provided with a 60 transparent pane 12 preferably formed from red glass in a manner well known in the art. An electric lamp receiving sleeve 13 is mounted in the rear of the compartment 11 directly behind the transparent pane 12. 65 The inner walls of the compartment are preferably coated with opaque material such as white paint so that a maximum amount of light will be deflected downwardly. It is of course apparent that the compartment 11 is 70 open at the bottom from one end to the other so that the light rays will be projected the full extent of the tag holder.

One end of the casing 7 is closed, as indicated at 14, by bending one of the terminals 75 thereof at right angles, this closed end serving as an abutment for one end of the license tag. The opposite end 15 of the casing is likewise closed but is relatively narrower than the closed end 14 for a purpose herein- 80 after set forth. As shown to advantage in Fig. 5, a right angled guide flange 16 is mounted on the upper face of the right angled portion 8 of the casing. One end of this guide flange is engaged with the front 85 face of the end 15 of the casing while the opposite end lies to the rear of a flange 16 which is formed on the closed end 14 of the casing.

A guard frame 17 is mounted on top of 90 the lip 9 and extends upwardly in front of and spaced from the front face of the end 15 of the casing. The frame has a portion thereof extending completely across the casing from the end 15 to the end 14 directly 95 below the compartment 11 so as to provide a license tag plate guiding rib which coacts with the lip 9. The license tag designated in the drawings at 18 is urged through the end 15 of the casing beneath the lip 9 and 100 frame 17. It will be observed that both ends of the casing have the front faces thereof obliquely disposed so that the tag, when in position, in the casing, will be in an angular position. As illustrated to advantage in 105 Fig. 3 the upper margin of the tag will lie in close proximity to the back of the casing directly below the compartment 11 while the lower marginal edge of the tag lies within the vertical plane of the front of said com- 110

partment. Therefore, the light rays will be projected downwardly over the entire face of the tag.

The rear face of the casing is provided with openings 19 which are adapted to conform to the shape of and are in alignment with the outer openings 20 formed in license tags. These openings 19 and 20 receive bolts 21 therethrough which bolts are customarily

10 used at the present time for securing license tags to vehicles. In this instance, the bolts are shown to be detachably engaged with a portion 22 of the same. Therefore, these bolts not only serve to support the license tag holder or casing but also prevent displacement of the license tag from its holder. However, when it is desired to remove the license tag the bolts 21 may be disengaged in an obvious manner.

20 In jurisdictions where it is necessary to carry two or more tags a casing such as that shown in Fig. 6 of the drawing may be used. This type of casing is identical with the construction above described except that the 25 portion of the casing beneath the illuminating compartment 11 is extended and is provided with a supporting flange 23 which is arranged about midway between the upper and lower ends of the tag receiving portion 30 of the case to provide an upper tag compartment 24 and a lower tag compartment 25.

From the above it will be apparent that a casing is provided which embodies a tail light together with a means for illuminating 35 a license tag or tags. By constructing the casing in the manner specified, an illuminating compartment is provided at the top which will concentrate its light rays directly

upon the license tags thereby rendering the indicia clearly discernible. It is understood 40 that the size of the casing may be varied to conform to different sizes of tags also that any material may be used which will be most suitable in carrying out the objects of this invention. It is appreciated that various 45 changes may be made in the device within the scope of the claims appended.

What is claimed is:—

1. In combination with a standard vehicle license tag having elongated longitudinally 50 extending slots near its upper margin, a holder for the tag including a casing which slidably receives the tag and retains the same at an inclination, said holder being provided with slots aligning with the slots 55 of said tag, and bolts engaged through the aligned slots of the tag and casing to support the latter on the vehicle and to retain the tag in the casing from displacement, the back of said casing, above the slots thereof, 60 being extended and equipped with an illuminating compartment which overhangs the license tag.

2. A device of the character described including a metal sheet, portions of the ends 65 of which diverge and are bent at right angles, one of said ends being extended to provide a license tag engaging abutment, the portion of the sheet above said right angled ends having the marginal edge thereof 70 turned inwardly at right angles to provide a flange, and an illuminating compartment engaged with said flange.

In testimony whereof I affix my seal.

HARRY F. WITTIG.
